(57) **CLAIM**

We claim the ornamental design for hygiene product caddy, as shown and described.

DESCRIPTION

FIG. 1 is a top, front, and side perspective view of the hygiene product caddy, showing our design.

FIG. 2 is a bottom, rear, and side perspective view of the hygiene product caddy.

FIG. 3 is a front elevational view of the hygiene product caddy.

FIG. 4 is a right-side elevational view of the hygiene product caddy.

FIG. 5 is a rear elevational view of the hygiene product caddy.

FIG. 6 is a left-side elevational view of the hygiene product caddy.

FIG. 7 is a top plan view of the hygiene product caddy; and, FIG. 8 is a bottom plan view of the hygiene product caddy.
